(57) **CLAIM**

The ornamental design for a point of sale terminal with advertising monitors, as shown and described.

DESCRIPTION

FIG. 1 is a front perspective view of a point of sale terminal with advertising monitors;

FIG. 2 is a front elevation view thereof;

FIG. 3 is a left side elevation view thereof;

FIG. 4 is a right side elevation view thereof; and,

FIG. 5 is a top plan view thereof.

The broken lines in FIG. 2 depict environmental subject matter only and form no part of the claimed design.
